AIR CONDITIONING METHOD AND APPARATUS

Agnew H. Bahnson, Jr., Winston-Salem, N. C.

Application June 5, 1942, Serial No. 445,947

7 Claims. (Cl. 261—22)

This invention relates to improvements in air conditioning method and apparatus and particularly to air conditioning method and apparatus of the type employing an air conveying and distributing duct having means for humidifying air within the duct and a plurality of outlets for distributing the moisture laden air to the space to be conditioned.

Air conditioning systems of this general type are particularly adapted to industrial air conditioning and have proved highly satisfactory in the conditioning of air in cotton textile mills, and the like. However, in large wet duct installations it has been found that due to the limits in the capacity of the air stream to evaporate and/or carry along as mist water introduced into the air stream by a water atomizing or vaporizing apparatus located at or adjacent the intake end of the duct, the deposition of entrained mist on the interior surfaces of the duct, and passage thereof out of the duct through the outlets nearer to the humidifying unit, the air passing to the outlets in the more remote portions of the duct carries little if any entrained mist into the space to be conditioned. This results in uneven conditioning of the space.

It is therefore a primary object of the invention to provide a novel method of supplying conditioned air to large spaces and an air conditioning system including a wet duct distributing and humidifying unit of novel construction which will supply air bearing substantially uniform quantities of water from all of the outlets throughout the length of the duct.

Another object of the invention is to provide air conditioning and distributing apparatus of the wet duct type including a novel and efficient arrangement of air propelling means and means for discharging finely divided water into the air whereby to effect over the entire length of the distributing duct discharge of air of uniformly high moisture content.

A further object of the invention is to provide an improved humidifying duct structure in which the air stream is divided and humidified in stages immediately preceding points of discharge into the space to be conditioned.

Other objects and advantages of the invention will be apparent from the following detailed description of the invention with reference to the accompanying drawings which illustrate a preferred embodiment of the invention by way of example and in which:

Fig. 1 is a top plan view of a preferred embodiment of the invention,

Fig. 2 is a section on the line 2—2 of Fig. 1,
Fig. 3 is a partial section on the line 3—3 of Fig. 1,

Figs. 4 and 5 are partial diagrammatic sections on lines 4—4 and 5—5, respectively of Fig. 1,

Fig. 6 is an enlarged vertical axial section through one of the outlet nozzles,

Fig. 7 is a similar view looking in the opposite direction,

10 Fig. 8 is a section on the line 8—8 of Fig. 6,
Fig. 9 is a front end elevation of a modified form of outlet nozzle,

15 Fig. 10 is a section on the line 10—10 of Fig. 11,
Fig. 11 is a side elevation of the modified outlet,

Fig. 12 is a similar view from the opposite side,
15 Fig. 13 is a section on the line 13—13 of Fig. 9,
Fig. 14 is a similar view looking in the opposite direction, and

20 Fig. 15 is a plan view of a modified apparatus embodying the invention.

Referring now more particularly to the form of the invention shown in Figs. 1 to 3, 10 indicates a distributing duct and humidifier casing which is adapted to extend across a room or space to be conditioned. The duct is preferably disposed so as to take in air from an outside air inlet 11 in the wall 12, but provision may also be made for recirculating air from within the space. The duct 10 tapers in form from adjacent the air inlet end to the opposite end thereof.

Adjacent the inlet end of the duct is a large axial flow fan 13 mounted on the shaft 14 centered in the duct and driven through a belt drive 15 from an electric motor 16 mounted outside the duct 10. The shaft 14 is journaled in suitable bearings 17 carried by a frame 18. Radial vanes 13' are provided adjacent the fan to eliminate the rotary component imparted to the air by the fan.

35 40 45 50 55 The section 10' of the duct 10 from a point adjacent the fan 13 to a point approximately intermediate the extremities thereof is divided into two substantially equal duct passages 19 and 20 by a vertical partition wall 21. The duct passage 19 is closed at the end opposite the fan 13 by an end wall 22. Means are provided for discharging finely divided water into the air adjacent the inlet end of the duct passage 19. This means preferably comprises an atomizing element 23 which is supported centrally in the passage on a bracket 24 fastened therein. The atomizing element includes a revolving disc 25 and an atomizer ring 26 supported by a casing 27. The disc 25 is mounted on a shaft 28 which extends through the casing 27 and mounts a pulley 29 driven by belt

drive 30 from the motor 16. Water is fed to opposite sides of the disc 25 through pipes 31 from a suitable source of supply.

The water atomizing unit and drive arrangement may be and preferably is in general similar to that disclosed in my copending application Serial No. 378,816 filed February 13, 1941.

A plurality of substantially horizontally disposed laterally directed outlet nozzles 32 are mounted in openings 33 in the outside wall of the duct passage 19 to distribute the moisture laden air into the space to be conditioned.

The fan 13 operating in the duct inlet zone common to the duct passages 19 and 20 forces air from the outside or recirculated air from the space to be conditioned into and through both duct passages.

The air propelled through the duct passage 20 passes therefrom into the end section 34 of the main duct 10 and is propelled therethrough by a fan 35 mounted on shaft 36 journaled in brackets 37 within the duct section 34 beyond the end wall 22 of the duct passage 19. The fan 35 is driven through a belt drive 38 by electric motor 39 mounted outside the duct. A second atomizing unit 40, similar in construction to the unit 23, but mounted coaxially with the fan 35, has the revolving disc 41 thereof driven through belt drive 42 by the motor 39. Radial vanes 35' are mounted in advance of unit 40.

A plurality of outlet nozzles 43 similar to the nozzles 32, mounted in lateral openings in the side of the duct section 34 between the second atomizing unit and the terminus thereof, distribute the moisture laden air from the duct section 34 into the space to be conditioned. Where the duct 10 extends completely across the space to be conditioned, the outlets 43 in the terminal half 34 are under some conditions preferably faced in the opposite direction to the outlets 32 so as to stimulate circulation of air in a circular path through the space.

The construction of the duct 10 and outlet nozzles therefor provides for facility of assembly, uniform distribution of air through the outlets from end to end of the duct and permits the supply of heavily moisture laden air from the duct outlets at high velocity while preventing the discharge into the air in the space to be conditioned of any particles or drops of water which will not completely evaporate before falling to the floor or onto machinery adjacent the outlet.

The duct sections are made of sheet metal and are preferably formed from strips or sheets which are bent into the tapered tubular shape with a longitudinal seam 44 uniting the meeting edges. The openings 33 in the wall of the duct sections for mounting the outlets are all preferably of the same size and pattern and are preferably cut or die pressed out before the sheets are bent into tubular form. These openings are substantially elliptical in shape with the major axis thereof normal to the longitudinal axis of the duct so that when the sheets are formed into tapered duct sections, the vertical dimension of the openings will be progressively less from end to end due to the progressive taper with which the duct is formed, as is illustrated by Figs. 3 to 5, which are sections at intervals along the length of the duct.

The duct outlet nozzles 32 and 43 are substantially conoidal in form and substantially elliptical in cross section with the major axis thereof disposed in the vertical plane and are preferably all of the same size. The side wall portions of the

outlet nozzles are slightly curved from top to bottom and the diameter of the nozzles between the side wall portions is progressively slightly greater from the outer to the inner extremity of the nozzles resulting in a slight taper from the inner to the outer end of this portion thereof as will be seen in Fig. 8. In the vertical dimension the outlet nozzles taper rather sharply from the largest diameter at the inner extremity thereof to the smallest diameter at the discharge end thereof as seen more clearly in Figs. 6 and 7.

As the outlet nozzles are all of the same construction a description of one will be sufficient.

The bottom wall portion of the outlet nozzle is formed with a sharper taper from the inner to the outer end than is the upper wall portion thereof so that when the outlet is mounted with the longitudinal central axis thereof approximately horizontal, the bottom wall will slant inwardly at a sufficient sharp angle to effectively drain back into the duct passage any moisture which collects on the walls and runs down to the bottom thereof. At the outer end of the outlet, the edge is turned inwardly as indicated at 45 to form a gutter which will collect and drain any moisture which may be deposited on the inner wall of the outlet and be forced toward the discharge end under influence of the air stream passing therethrough. To further facilitate drainage of collected water back into the duct the outlet is provided at the bottom with a double wall by means of an auxiliary wall member 46 attached thereto and defining with the bottom wall portion 47 a protected drainage channel 48 shielded from the main air stream issuing through the duct. At the points of juncture of the auxiliary wall 46 with the main wall of the outlet a series of openings 49 are formed in the wall 46 to facilitate drainage of moisture from the side walls into the protected drainage channel 48.

The portion of the wall of the outlet extending into the duct is formed so that at the top and bottom the outlet projects a substantial distance into the duct passage. From the top, the inner edge of the side wall portion 50 nearest the inlet or supply end of the duct is cut away along a generally curved line, which midway of the height of the outlet installed at the larger end of the duct is almost coincident with the side wall of the duct passage. The inner edge of the side wall portion 51 remote from the inlet end of the duct follows a generally straight line from top to bottom so as to project into the air stream in the duct and act somewhat as a scoop in diverting a part of the air into and through the outlet.

It will be observed that the windward surface of the side wall 51 being directly impinged by the moisture laden air stream will quickly become wet and any heavy drops of moisture deposited thereon will spread out in a film and run down into the drainage channel 48 at the bottom without causing any trouble. However due to the existence of a slight back draft along and adjacent the dry sheltered or lee side of the wall portion 50 caused by the aspirating effect of the air stream turning outwardly through the outlet, the collection of moisture on the outer or windward surface of the wall portion 50 adjacent the top thereof or on the inside surface at or adjacent the top where the wet and dry areas meet, exhibits a tendency to form drops adjacent the inner edge of the upper portion of the outlet, which drops if allowed to form and fall free would be picked up and carried out into the room by the air stream. The tendency to the

formation and deposit of drops in this area is probably due to the direction of the air currents after impingement against the upper portion of the windward side of the inwardly projecting wall portion 50 plus the effect of the aspirated air current flowing back along the dry inner surface on the wall portion of the outlet. In order to take care of this condition, the outlet is formed with a knurled surface 52 along and adjacent the inner edge thereof at the top in the region where the wet and dry areas meet and the knurling is extended down on the windward wall portion 50 to a point where the edge of the outlet curves well into the duct and air stream so that any moisture depositing on the outlet wall portion 50 adjacent the edge will be prevented from forming into drops at the edge and will be filmed out by contact with the knurled surface and will flow down the side to the bottom where it will drain into the main duct passage. A wire mesh screen folded over the edge in the same area may replace the knurled surface and will have the same effect. The auxiliary wall portion 46 at its inner end is formed with a sharply downturned inwardly projecting extension 53 which shields the inner end of the drainage channel so as to obviate any possibility of the inwardly deposited water being picked up and carried through the outlet by the force of the air stream.

In cotton and other mills where there is a considerable amount of lint and the like in the air, the aspirating effect of the air stream issuing from the outlet induces air currents along and over the outside surface and tip of the outlets, causing a deposit of lint on the tip of the outlets due to the fact that these are usually slightly wet at this point. In order to overcome this condition the outlets are provided with an outstanding rib or annular flange 54 adjacent the tip end thereof which serves to divert the aspirated lint laden air currents from the damp area at the extremity thereof and prevent the deposit of lint on these surfaces.

The outlet fittings are dimensioned and the openings in the side walls of the duct are formed so that the outlets turned on the side and slightly flattened may be inserted bodily into the duct through the openings, turned and pulled back outwardly in correct position and snugly fitting the edges of the openings. When the outlets are pulled outwardly they readily resume the correct shape to form a tight fit all around the edges of the opening as the sheet metal construction has sufficient flexibility to permit the side walls to flex outwardly when the top and bottom portions engage the top and bottom edges of the openings.

Although the outlets are frictionally held in place due to the manner of installation, novel fasteners are provided for securing them against displacement. These features consist of a plurality of metal strips 55, having one end thereof riveted or otherwise attached at 56 on the outside of the outlets adjacent the inner end of the same. The point of attachment of the strips 55 is at a point on the outlet which in all positions of installation will remain within the duct and the strips extend forwardly from the point of attachment so as to extend outside the duct in every case. During installation of the outlets the strips 55 lie flat on the surface and when the outlets are drawn outwardly to jam into final position the free ends 57 of the strips, extending outwardly of the duct wall, are bent out into contact with the wall thus securing the outlets against

displacement. This construction is extremely simple, avoids the use of nuts, bolts or solder in securing the outlets and forms a universal fastener for all the outlets in an installation because all that is necessary is that the strips be long enough to extend out beyond the point of engagement of the edge of the duct wall on the outlets.

It will be noted that the uniformly dimensioned openings 33 formed in the metal sheets from which the duct sections are made progressively change in profile when the duct is formed because as the taper progresses, the curvature of the walls become sharper, thereby progressively shortening the transverse chord of the openings. Therefore, when the uniformly dimensioned outlet nozzles are installed in these openings, as above described, due to the tapered form thereof, they come into engagement with the edges of the openings at progressively higher positions on the nozzles so that progressively greater portions of the nozzle members remain projecting into the duct. The progressively greater projection of the nozzle members into the tapering duct effects automatically a proportioning of the air delivered from the nozzles over the length of the duct.

The described construction and manner of assembling the duct and outlets effects a great saving in labor and time in the installation of the system because all of the work of cutting of the outlet openings and forming of the outlets can be standardized in the factory rather than individually cutting the outlet openings and individually trimming and fitting the nozzles thereto on the job as has heretofore been the practice.

The modified form of duct outlet 60 shown in Figs. 9 to 14 is formed with a generally elliptical cross section and an inturned outer edge 61 for trapping and draining moisture filmed on the inner wall surfaces thereof. In this form of outlet, the lower main wall portion 62 is formed with a curvature greater than that of the corresponding edge portion of the opening in the duct in which it is installed and the vertical dimension from top to bottom is less than the corresponding dimension of the opening. The outlet is formed with an auxiliary wall portion 65 applied on the outside of the bottom portion 62 thereof and having a curvature less than that of the adjacent portion of the outlet and the same as the adjacent portion of the opening in the duct thereby producing between the main and auxiliary wall portions a drainage channel 66 opening rearwardly into the duct passage. The auxiliary wall portion 65 extends forwardly a considerable distance beyond the outer edge of the outlet thereby forming a lip 67 adapted to catch any heavy drops of moisture carried out of the outlet by the air stream. The lip is dimensioned to catch any drops heavy enough to fall out of the air stream and deposit on machinery or floor adjacent the outlet before becoming completely evaporated. The lip slants back at a sufficiently sharp angle to effectively drain moisture caught thereon and the outer edge thereof is turned inwardly at 68 to form a trapping gutter insuring the retention of moisture therein against blowing over the edge.

The auxiliary lip forming wall portion extends at its lateral edges into contact with the outlet walls and is attached thereto by soldering or riveting at 69, so that as viewed from the outside, the auxiliary wall forms the bottom continuation of the elliptical wall of the outlet. The outlet therefore makes a snug fit in the opening

in the duct wall which is formed to accommodate an elliptically shaped outlet structure and when the outlet is installed as previously described in connection with the other form, a tight solderless fit is effected.

In the form of the invention shown in Fig. 15, the main duct 110 is formed without any internal dividing partition and all of the air propelled into the duct by the fan 113 is passed around the atomizing unit 123 which is centered in the duct and driven from the same motor 116 as the fan. In this construction there is mounted in the duct beyond the first set of outlets 132 a humidifying unit 141 driven by a motor 139. The humidifier unit 141 serves to replenish the supply of moisture in the air stream flowing to the second or terminal group of outlets 143, which replenishment is necessary because of the loss of moisture represented by deposition on the duct walls and the passage of unevaporated finely divided particles out of the first set of outlets.

Although a preferred method of supplying conditioned air and preferred forms of apparatus for practicing the method have been described and illustrated by way of example, it will be understood that other modifications embodying the invention may be resorted to without departing from the spirit of the invention within the scope of the appended claims.

I claim:

1. The method of supplying conditioned air to a plurality of points of discharge in a space to be conditioned from an air intake at one side of said space which comprises propelling air from the intake point through a zone of advancement adjacent the air intake, humidifying the air adjacent the zone of advancement, discharging successive portions of the humidified air from discharge points spaced along the zone of advancement, passing the remaining portion of the air through a humidifying zone remote from said zone of advancement, humidifying the air passing through said humidifying zone and discharging the same from a series of spaced points of discharge remote from said zone of advancement.

2. The method of supplying conditioned air to a plurality of points of discharge into a large space to be conditioned from an air intake at one side of the space which comprises propelling the air from the intake point through a zone of advancement in the direction of the points of discharge to said space, dividing the air into a plurality of streams, humidifying one of the air streams and discharging the same from a series of points of discharge at different distances from and relatively near the intake point, propelling the other air stream through a second zone of advancement spaced from the first zone of advancement, humidifying the air stream from the second zone of advancement and discharging the same into the space to be conditioned from a series of points of discharge at different distances from and relatively remote from the intake point.

3. The method of supplying humidified air to a space to be conditioned from an air intake point substantially remote from portions of said space, which comprises propelling air from the point of intake to a plurality of zones of discharge spaced from each other along the path of propulsion of the air, discharging finely divided water into the air immediately in advance of each of the zones of discharge, and discharging air and entrained particles of moisture from a series of longitudi-

nally spaced points in each of the zones of discharge into the space to be conditioned.

4. Apparatus for supplying conditioned air to a space to be conditioned comprising an elongated air conveying and distributing duct extending within the space to be conditioned and having an air intake at one end thereof, a plurality of sets of outlets for humidified air spaced along the length of said duct from adjacent the intake to the remote end thereof, blowing means adjacent the intake for propelling air into and through said duct, means between said blowing means and a first set of outlets for discharging finely divided water into the duct for entrainment in the air supplied by said blowing means for discharge through said outlets, and means in said duct between said first set of outlets and a second set of outlets in the succeeding portion of said duct for discharging finely divided water into the duct for entrainment in the air supplied by said blowing means to said succeeding portion of said duct for discharge through said second set of outlets.

5. In apparatus for supplying conditioned air to a space to be conditioned, an elongated air conveying and distributing duct extending into said space, a plurality of outlets for humidified air spaced along the length of said duct, means at one end of said duct for propelling air into and through said duct to said outlets, a longitudinal partition within said duct extending from adjacent said propelling means to a point intermediate the ends of said duct and defining independent duct passages each serving a plurality of said outlets, means in each of said duct passages in advance of the first of the outlets served thereby for discharging finely divided water into the air flowing thereto, and auxiliary air propelling means in advance of the water discharge means in the duct passage remote from said first mentioned propelling means.

6. In apparatus for supplying conditioned air to a space to be conditioned through a plurality of spaced points of discharge from an air intake point adjacent one side of the space comprising an elongated air conveying and distributing duct extending into said space from the point of air intake, a plurality of longitudinally spaced outlets for humidified air arranged in groups succeeding each other at spaced intervals along the length of said duct, means for propelling air from the intake point into and through said duct and for supplying air in separate streams to the respective groups of discharge outlets, means for discharging finely divided water into the respective air streams immediately in advance of each of said groups of outlets, and air propelling means in advance of the means for discharging water into the air stream supplied to the group of outlets remote from the point of air intake.

7. Apparatus for supplying conditioned air to a space to be conditioned comprising an elongated air conveying and distributing duct extending within the space to be conditioned and having an air intake at one end thereof, a plurality of sets of outlets for humidified air spaced along the length of said duct from adjacent the intake to the remote end thereof, blowing means adjacent the intake for propelling air into and through said duct, means between said blowing means and a first set of outlets for discharging finely divided water into the air supplied by said blowing means for discharge through said outlets, means in said duct between said first set of outlets and a second set of outlets in the succeeding portion of said duct for discharging finely divided water into the

air supplied by said blowing means to said succeeding portion of said duct for discharge through said second set of outlets, said outlets comprising a tubular member extending laterally through the duct wall and tapering from an end thereof within the duct to a discharge end without the same, the wall of said outlet at the discharge end being turned inwardly to define a gutter for trapping moisture deposited on the inner surfaces thereof,

the bottom portion of said outlets being formed with inwardly slanting spaced wall portions defining a drainage channel discharging into the duct, the windward side of the outlet wall within the duct being cut away toward the adjacent duct wall and the leeward side of the same extending into the duct passage to divert air into said outlet.
